UNITED STATES PATENT OFFICE

ANTON FAZEKAS, OF SAN FRANCISCO, CALIFORNIA

DESIGN FOR A LETTER BOX PLATE

Application filed December 21, 1932. Serial No. 46,544. Term of patent 14 years.

To all whom it may concern:

Be it known that I, ANTON FAZEKAS, a citizen of the United States of America, residing in the city and county of San Francisco, State of California, have invented a new, original, and ornamental Design for a Letter-Box Plate, of which the following is a specification, reference being had to the accompanying drawing, forming part thereof.

Fig. 1 is a plan view showing my letter-box-plate;

Fig. 2 is a front elevation showing the same; and

Fig. 3 is an end elevation showing the same.

I claim:

The ornamental design for a letter box plate, as shown.

ANTON FAZEKAS.
